UNITED STATES PATENT OFFICE.

WILLIAM H. ROBINS, OF MINNEAPOLIS, MINNESOTA, ASSIGNOR TO AMERICAN BANK PROTECTION CO., OF MINNEAPOLIS, MINNESOTA.

CIRCUIT-CLOSING DEVICE FOR BURGLAR-ALARM SYSTEMS.

No. 853,736.

Specification of Letters Patent.

Patented May 14, 1907.

Application filed December 6, 1905. Serial No. 290,569.

To all whom it may concern:

Be it known that I, WILLIAM H. ROBINS, of Minneapolis, Hennepin county, Minnesota, have invented certain new and useful 5 Improvements in Circuit-Closing Devices for Burglar-Alarm Systems, of which the following is a specification.

In the construction of a burglar alarm system it is customary to provide a guard or shield over the gong, to prevent it from being tampered with and rendered inoperative by a burglar or other person. To prevent the ringing of the gong, where access to it directly is prevented by means of a shield or guard, 10 some burglars have adopted the method of filling the gong and shield with sand, thereby deadening the sound of the hammer, if not entirely preventing its operation. This sand, or other foreign material, can usually 15 be filled in between the shield and the gong without bridging the space between the inner and outer shell, and thereby closing the alarm circuit, and, consequently, it has been found desirable and I have made it the object of my present invention to provide a device preferably located below the gong near the bottom of the inner shell of the shield, which when sand or other foreign material is 20 poured into the shield, will be actuated to 25 close the alarm circuit.

The invention consists, generally, in a device arranged to be actuated by the weight of the foreign material filled in between the gong and shield to close a local circuit and 30 release the drop, which in turn when operated will close the alarm circuit and sound the gong before any considerable amount of foreign material can be inserted into the shield.

40 In the accompanying drawings forming part of this specification, Figure 1 is a vertical sectional view through the shield illustrating the mechanism inclosed thereby. Fig. 2 is a similar sectional view taken on a 45 section line substantially at right angles to the section line of Fig. 1. Fig. 3 is a plan view of the circuit-closing device. Fig. 4 is a longitudinal sectional view of the same.

In the drawing, 2 represents a back plate 50 whereon the shield, consisting of an outer shell 3 and an inner shell 4 separated by an air space but connected by suitable insulated screws 5, is secured. A hollow stud 6 is connected with the outer shell, and projects

through the inner one and the base 2. A 55 gong 7 is mounted on the said base and has a suitable hammer 8 connected with the armature 9 that is actuated when the circuit is closed through the magnet 10. The magnet is mounted on a suitable frame 11 and in circuit therewith, and contact springs 12 are carried by said armature and are adapted to engage a contact screw 13 which is mounted in the said frame and insulated therefrom and in circuit with a post 14, to which a wire 60 65 15 is attached. This wire runs to a battery B and from thence to a post 16 connected with a frame 17 of a circuit closer 18, which I will designate as the primary one. The contact point 19 of this circuit closer, which 70 forms the subject matter of a companion application herewith, is connected by a wire 20 with a post 21 on the frame 11, and said post has a connection 22 through the magnet 10 with the said frame. Below the gong 7 a box 75 23 is arranged containing a chamber 24, wherein a spoon-shaped secondary circuit-closing device 25 is centrally pivoted upon a bracket 26. A cover 27 is provided on said box having an opening 28 directly above the 80 bowl of the circuit closer. The handle of the circuit closer has a slot 29 with a weight device 30 adjustably mounted thereon and adapted to be moved back and forth in said slot until it barely overbalances the weight of 85 the bowl and causes it to swing upward against the box cover, as indicated in Fig. 4. A contact post 31 is provided beneath the bowl of the circuit closer in position to be engaged thereby when any foreign material falls 90 through the hole 28 into the bowl and depresses the same. A wire 32 leads from the post 31 to the frame 11. A second post 33 is provided in the bottom of the box in circuit with the bracket 26 and connected by the 95 wire 34 with a contact post 35 on the inner shell of the shield. A wire 36 extends from the post 35 to the magnets of the primary circuit closer 18.

The local circuit is normally broken between the bowl of the secondary circuit closer and the post 31. When, however, this bowl is depressed the circuit will be closed between the posts 31 and 33 through the circuit closer frame 17 to release the drop and 100 close the main or alarm circuit. The closing of this local circuit will take place whenever 105 any foreign material, such as sand, is filled

in to the space between the gong and the inner shell of the shield, as the sand flowing down into the bowl of the spoon-shaped circuit closer will immediately depress the same to contact with the post 31 and close the circuit. Normally, however, the weight of the device 30 will be sufficient to hold the bowl of the circuit closer out of contact with the post 31. The secondary circuit closer 10 will also be operated if any material in liquid form is deposited in the space inclosed by the inner shell of the shield; and it will be impossible for a burglar, or any unauthorized person, to tamper with the system and attempt to 15 render the gong inoperative, by inclosing it with a foreign material without actuating the spoon-shaped circuit closer and closing the alarm circuit.

It is desirable in a device of this kind to 20 provide means for closing the alarm circuit, should an attempt be made to pierce the shield and thereby momentarily establish a metallic short circuit between them. With this end in view I provide a wire 37 25 connecting the stud 6 with the wire 15. This wire 15 through the circuit closer and the wire 36 is connected with the post 35 on the inner shell of the shield, and the stud 6, as heretofore stated, is connected with the outer shell of the shield; and, consequently, any 30 attempt to bore through the shield with a tool of any kind will form a metallic bridge or connection between the inner and outer shell and close the local circuit through the 35 primary circuit closer 18 and release the drop to close the alarm circuit.

I claim as my invention:

1. The combination with an alarm circuit having a gong, of a shield inclosing said gong, 40 a circuit closer arranged in the lower part of said shield and having a suitable receptacle, said circuit closer being connected with said alarm circuit and arranged when actuated, to close the same, and the inner walls of said shield being curved and adapted to direct sand or foreign material deposited in the shield into said receptacle, substantially as described.

2. The combination, with an alarm circuit 50 having a gong, of a shield inclosing said gong, a circuit closer arranged in the lower part of said shield and having a suitable receptacle, said circuit closer being connected with said alarm circuit and arranged when actuated to close the same, and the inner walls of said shield being arranged to direct sand or foreign material deposited in the shield into said receptacle.

3. The combination, with an alarm circuit 60 having a gong, of a shield inclosing said

gong, a circuit closer pivoted at a point intermediate to its ends and having a bowl or depression in one end and a counter balance on its other end, and connected with said alarm circuit, the bowl of said circuit closing 65 device being adapted to receive sand or any foreign material deposited in the shield, and a contact point arranged beneath the said bowl to be engaged thereby to close said alarm circuit.

4. The combination, with an alarm circuit having a gong, of a shield inclosing said gong, a tilting circuit closing device centrally pivoted in said shield and connected with said alarm circuit and having a bowl or 70 receptacle adapted to receive sand and foreign material deposited in said shield, a counter balance mounted on the handle portion of said circuit closing device and normally balancing the weight of said bowl, and 80 a contact point connected with said alarm circuit and located beneath said bowl and engaged thereby when said bowl is depressed by the weight of the material therein.

5. The combination, with an alarm circuit 85 having a gong, of a shield inclosing said gong, a circuit closing device centrally pivoted in said shield and connected with said alarm circuit, one end of said circuit closing device having a receptacle adapted to receive sand and foreign material deposited in said shield, and the other end of said circuit closing 90 device having a slot and a counter balance weight mounted therein and adapted to be adjusted to balance the weight of said receptacle, and a contact point connected with said alarm circuit and located in the path of said receptacle, whereby depression of the same under the weight of the foreign material will close the said alarm circuit.

6. The combination, with an alarm circuit having a gong, of a shield inclosing said gong, a box arranged in the lower part of said shield and having a chamber or recess, and a plate arranged over said chamber and provided with an opening leading to said recess, a tilting circuit closing device arranged in said chamber and having a bowl adapted to receive sand or foreign material deposited in said shield, and a contact point connected with said alarm circuit and located in the path of said bowl, whereby the alarm circuit will be closed when the bowl has tilted a predetermined distance.

In witness whereof, I have hereunto set my hand this 22nd day of November 1905.

WILLIAM H. ROBINS.
